US0D1099902S

(12) **United States Design Patent** (10) **Patent No.:** **US D1,099,902 S**
(45) **Date of Patent:** **** Oct. 28, 2025**

(54) **KEYBOARD**

(71) Applicant: **Logitech Europe S.A.**, Lausanne (CH)

(72) Inventors: **Nicholas Jinkinson**, St-Sulpice (CH); **Marcel Twohig**, Dublin (IE); **Stone Wang**, Hsinchu (TW); **Jasper Phua**, Morges (CH); **Olivia Hildebrand**, Geneva (CH)

(73) Assignee: **Logitech Europe S.A.**, Lausanne (CH)

(**) Term: **15 Years**

(21) Appl. No.: **29/910,905**

(22) Filed: **Aug. 25, 2023**

Related U.S. Application Data

(63) Continuation of application No. 29/856,447, filed on Oct. 13, 2022, now Pat. No. Des. 1,000,442, which is a continuation of application No. 29/684,715, filed on Mar. 22, 2019, now Pat. No. Des. 970,502.

(57) **CLAIM**

The ornamental design for keyboard as shown and described.

DESCRIPTION

FIG. 1 is a perspective view from the upper front, right side of the keyboard showing our new design;

FIG. 2 is a perspective view from the upper back, left side thereof;

FIG. 3 is top plan view thereof;

FIG. 4 is a bottom plan thereof;

FIG. 5 is a front elevation view thereof;

FIG. 6 is a back elevation view thereof;

FIG. 7 is a left side elevation view thereof; and,

FIG. 8 is a right side elevation view thereof.

The even-dash broken lines depict portions of the keyboard that form no part of the claimed design. The dash-dot broken lines represent boundaries of the claim and form no part of the claimed design.

1 Claim, 5 Drawing Sheets
